UNITED STATES PATENT OFFICE.

THOMAS ALDIN CRABTREE, OF BANGOR, MAINE, ASSIGNOR TO J. P. GREELEY,
OF SAME PLACE, AND H. A. ALKON, OF BOSTON, MASSACHUSETTS.

DESIGN FOR A CARD OR LETTER RACK.

SPECIFICATION forming part of Design No. 18,519, dated August 14, 1888.

Application filed June 23, 1888. Serial No. 278,052. Term of patent 7 years.

To all whom it may concern:

Be it known that I, THOMAS ALDIN CRABTREE, a citizen of the United States, and a resident of Bangor, in the county of Penobscot and State of Maine, have invented a certain new and original Design for Card-Files; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of this invention, and is a front view. Fig. 2 is a side view.

The invention relates to a new and original design in wire card or letter racks; and it consists in the novel form and configuration, as hereinafter set forth and illustrated in the accompanying drawings.

Referring to the drawings, A designates the rack, having the surface configuration representing a rope.

²⁵ B represents the parallel sides of the frame,

and C C' the outwardly-curved top and bottom thereof. The eye D at the top C is formed with the twisted shank E, as shown, and an eye, F, is formed at the bottom by turning the central portion of the curve C outward. ³⁰

G designates the pockets or racks springing from the sides B by a short rope-like portion, H, and having the inner ends terminating in a convolute curve, I, on a plane with the sides B. The pocket G stands out from the sides B, ³⁵ and is bent upwardly in a semicircular form.

Having described the design, I claim—

The design for a card-rack herein shown and described, the same consisting of the parallel sides, the outwardly-turned ends, and the ⁴⁰ pockets springing from the sides and having the inner ends turned in a convolute form, the whole having the surface configuration of a rope.

In testimony whereof I affix my signature in presence of two witnesses.

THOMAS ALDIN CRABTREE.
